(57) **CLAIM**

The ornamental design for air race gates, in two embodiments, as shown and described.

DESCRIPTION

FIG. 1 is a front side view of a first embodiment of air race gates having parallel gates according to the present invention; FIG. 2 is a left side view of the air race gates as shown in FIG. 1;

FIG. 3 is a back side view of the air race gates as shown in FIG. 1;

FIG. 4 is a right side view of the air race gates as shown in FIG. 1;

FIG. 5 is a top view of the air race gates as shown in FIG. 1; FIG. 6 is a bottom view of the air race gates as shown in FIG. 1;

FIG. 7 is a front side view of a second embodiment of air race gates having a single gate according to the present invention; FIG. 8 is a left side view of the air race gates as shown in FIG. 7;

FIG. 9 is a back side view of the air race gates as shown in FIG. 7;

FIG. 10 is a right side view of the air race gates as shown in FIG. 7;

FIG. 11 is a top view of the air race gates as shown in FIG. 7; and,

FIG. 12 is a bottom view of the air race gates as shown in FIG. 7.

UNITED STATES PATENT AND TRADEMARK OFFICE
CERTIFICATE OF CORRECTION

PATENT NO. : D633,963 S
APPLICATION NO. : 29/307448
DATED : March 8, 2011
INVENTOR(S) : Martin Jehart and Michael Arnold

Page 1 of 1

It is certified that error appears in the above-identified patent and that said Letters Patent is hereby corrected as shown below:

In the CLAIM section on Page 1, Column 2, cancel the text “The ornamental design for air race gates, in two embodiments, as shown and described.”, and insert the following claim:

--The ornamental design for the Air Race Gate, as shown and described.--

In the DESCRIPTION section on Page 1, Column 2, lines 13-35 cancel the text beginning with “FIG. 1 is a front side view of a first embodiment” and ending with “FIG. 12 is a bottom view of the air race gates as shown in FIG. 7.”, and insert the following description:

--FIG. 1 is a front view of the Air Race Gate showing our new design in association with a second gate in broken lines;

FIG. 2 is a right side view thereof;

FIG. 3 is a rear view thereof;

FIG. 4 is a left side view thereof;

FIG. 5 is a top view of the claim and an associated second gate in a modified orientation, wherein the upper ends are tilted slightly inward relative to the positions shown in FIG. 1;

FIG. 6 is the bottom view opposite to FIG. 5;

FIG. 7 is the front view of the claimed Air Race Gate standing alone;

FIG. 8 is the right side view thereof;

FIG. 9 is the rear view thereof;

FIG. 10 is the left side view thereof;

FIG. 11 is the top view thereof shown as an oblique angle similar to FIG. 5;

FIG. 12 is the bottom view thereof.--

Signed and Sealed this
Fourteenth Day of June, 2011

David J. Kappos
Director of the United States Patent and Trademark Office
